LIQUID DISPENSING DEVICE

Karl Heller, Jersey City, N. J., assignor to Felco
Faucet Corporation, Jersey City, N. J., a cor-
poration of New Jersey

Application August 8, 1934, Serial No. 738,907

5 Claims. (Cl. 251—132)

The improvements relate primarily to dispensing devices, commonly referred to as faucets, for beer, wines and other beverages but are adaptable to other uses and purposes. The objects of the 5 improvements, among others, are to provide an efficient, durable, strong and relatively simple device of this character which will stand up and function under all ordinary conditions of use, will not get out of order, may be quickly and easily 10 adjusted and without disconnecting any of its parts to take up wear, and will not retain any of the liquid therein to become stale, cause fouling of the parts and give rise to unsanitary conditions, but will permit the last drop of the liquid 15 passing from the liquid supply column to discharge therefrom leaving a clean, sanitary dry discharge chamber and spout. Other objects and advantages of the improvements will appear to those skilled in the art from the following specification and the accompanying drawing.

In the dispensing of beer, wines and other like beverages, it is common practice to employ a discharge tube of block tin or other metal or mineral—such as porcelain—which will not be easily 25 corroded and will not contaminate or spoil the taste of the liquid beverage. So far as I am aware, however, all dispensing devices heretofore employed are so constructed and arranged that when the dispensing valve is closed small quantities 30 of the liquid will have an opportunity to lodge and remain in the dispensing device between the valve and the mouth of the discharge spout and thus be exposed to air. As most beverages contain sugar, yeast germs and other matter which 35 will ferment or otherwise spoil when exposed to air and atmospheric temperatures, these dispensing devices become fouled and contaminated, and when permitted to stand out of use for a considerable period will permit unsanitary conditions 40 to arise therein and which will contaminate the beverage afterwards drawn therethrough. It is to avoid such conditions that the present improvements are primarily designed.

The improvements are illustrated in the accompanying drawing, referred to herein, in which—

Fig. 1 is a longitudinal, vertical section of a dispensing device embodying the improvements; and

Fig. 2 is an end elevation.

In the drawing 1 represents the discharge tube, which is preferably of block tin or other suitable material, 2 is a surrounded threaded sleeve running through the partition 3 and fixed thereon with the tube by means of a nut 5 and a bell shaped member 4. The tube 1 is connected with

the supply pipe 6 having a sleeve 7 by means of the clamping nut 8 threaded on one end of the sleeve 2. At the forward or discharge end of the tube 1 a valve seat member 9 is soldered or similarly secured as indicated at 10, so that the two 5 are united by an air and liquid-tight joint. Surrounding this end of the tube 1 is the plug or collar 11. The plug 11 is threaded onto the forward end of the sleeve 2 and fits snugly in the member 4, to which it is also threaded. 10

The forward end of the tube 1, at its discharge mouth, is flared as indicated at 15 and the valve seat 14 of the seat member 9 is beveled to receive the valve plug 16, which is preferably a steel ball threaded on the end of the stem 13. A valve body 12 providing a discharge chamber in front of the valve and having a downwardly extending spout 17 is screw threaded to the plug 11, and so formed interiorly that a smooth path is provided for the liquid passing from the valve and down through 20 the spout 17. It will be observed that by this arrangement no opportunity for the lodgment of liquid between the valve and the mouth of the discharge spout is afforded, so that when the valve is closed the last drop of liquid will flow 25 down through the spout and escape, and the spout and discharge chamber of the valve body will become clean and dry. By this arrangement provision is made against any fouling or contamination of the discharge chamber and spout, so that 30 the device will be clean and sanitary and will not contaminate or spoil the flavor of liquid drawn therefrom after the device has been out of operation for a period. 35

The stem 13 has an enlarged outer end 18 with a rounded extreme outer surface 18^a to co-operate with the eccentric 19 keyed to the shaft 20 mounted in the valve body 12 and rotated by the handle 26 fixed to the ends of the shaft by means of its arms 13^a. By this arrangement the valve plug 16 is moved to the left when the handle 26 is pressed downwardly, by the action of the eccentric 19 against the rounded end 18^a of the stem 13, and the valve is opened. To return the valve to closed position and the handle to its upper position, a spring 21 of rust-proof metal is provided. This spring is confined between the valve seat member 9 and the shoulder formed by the head 18 on the stem 13, and compressed at all times between these parts. The movement of the valve stem in valve opening direction places the spring 21 under further compression, so that when pressure on the handle 26 is released the plug 16 is seated against the valve seat 14 and the handle 26 moved to its upper position, as in- 45 50 55

dicated in dotted lines, by pressure of the head 18 against the eccentric 19. To adjust the valve, if necessary to take up wear, the eccentric 19 may be replaced by one slightly larger, or the valve plug 16 may be replaced. The eccentric may be renewed without opening the valve, and while the dispensing device is in operative position and the liquid supply pipe with liquid in it connected therewith.

10 A stop 22 on the valve body 12 limits the upward movement of the handle 26, and its downward movement is limited by contact with the cap 23 threaded on the outer end of the valve body. The removal of this cap affords access to 15 the eccentric and the shaft on pivot 20, for cleaning, or lubrication or replacement and permits the handle 26 to drop to a pendent position. A cork packing ring 24 seals off the interior of the valve body through which the liquid is 20 discharged, and this ring is held in position and compressed by a washer 25 threaded in the valve body and surrounding the end of the plug 18. This plug 18 is held in substantially horizontal 25 position at all times by the ring or washer 25, the packing ring 24 and the annular flange 27 in the interior of the valve body, but the opposite end of the stem 13 carrying the plug 16 will be permitted to have a slight lateral or oscillatory movement, so that the plug can seat itself at all 30 times accurately on the valve seat and close the discharge aperture securely. This ability of the plug to accommodate itself at all times to the seat is an important feature of the improvements.

35 The valve stem 13, the interior surfaces of the valve body which are exposed to the liquid and the spring are plated with or made of tin or other suitable non-corrodible, rustless metal, and the valve seat member 9 and valve plug 16 may also 40 be made of similar metal. It will be seen that the improvements provide a sanitary seal and dispensing conduit between the liquid supply pipe and the discharge mouth of the spout.

I claim:

45 1. In a liquid dispensing device, a dispensing tube of material non-corrodible by the liquid, means for connecting the same in communication with a conduit from a source of liquid supply, means for mounting said tube in fixed position, a 50 valve seat member united with the discharge end of said tube and extending beyond the same, said member having a valve seat therein through which the liquid is discharged from the discharge end of said tube, said valve seat located in the 55 discharge mouth of said tube and forming in effect a partial closure of the end of said tube, a metallic ball providing a valve plug adapted to engage said seat to close the discharge end of the tube, means for moving said plug into and out of contact with said seat to close or open the discharge mouth of said tube including a cam adapted to cock open the valve by frictional engagement with said plug-moving means and snap closed upon removal of said frictional engagement, a valve body enclosing said discharge end seat and plug, said valve body having a discharge 60 spout extending downwardly from immediate proximity to the end of the tube and said tube communicating directly therewith.

70 2. In a liquid dispensing device, a dispensing tube of material non-corrodible by the liquid, means for connecting the same in communication with a conduit from a source of liquid supply, means for mounting said tube in fixed position, a 75 valve seat member united with the discharge end

of said tube and extending radially beyond the same, said member having a valve seat therein through which the liquid is discharged from the discharge end of said tube, said valve seat located in the discharge mouth of said tube and forming in effect a partial closure of the end of said tube, a metallic ball providing a removable valve plug adapted to engage said seat to close the discharge end of the tube, means for moving said plug into and out of contact with said seat to close or open the discharge mouth of said tube comprising a valve actuating stem, a compression spring and an eccentric adapted to cock open the valve by frictional engagement with said plug-moving means and snap closed upon removal of said frictional engagement, a valve body enclosing said discharge end seat and plug, said valve body having a discharge spout extending downwardly from immediate proximity to the end of the tube and said tube communicating directly therewith, the end of said tube being united with said seat member by material of relatively low fusibility.

3. In a liquid dispensing device, a dispensing tube, means for connecting the same in communication with a conduit from a source of liquid supply, means for mounting said tube in fixed position, a valve seat member united with the discharge end of said tube and extending beyond the same, said member having a valve seat therein through which the liquid is discharged from the discharge end of said tube, said valve seat located in the discharge mouth of said tube and forming in effect a partial closure of the end of said tube, a steel ball adapted to engage said seat to close the discharge end of the tube, means for moving said ball into and out of contact with said seat to close or open the discharge mouth of said tube, comprising a valve stem mounted for reciprocation and carrying said ball, a spring engaging said stem and constantly urging it to closed position, an eccentric operatively associated with said stem and positioned for engaging same by frictional contact for cocking the valve in open position, a handle for operating said eccentric and arranged to be moved to closed position thereby through the stem moving action of the spring, and guiding means for said stem removed from said ball and permitting limited lateral movement of the ball.

4. In a liquid dispensing device, a dispensing tube, means for connecting the same in communication with a conduit from a source of liquid supply, means for mounting said tube in fixed position, a valve seat member united with the discharge end of said tube and extending beyond the same, said member having a valve seat therein through which the liquid is discharged from the discharge end of said tube, said valve seat located in the discharge mouth of said tube and forming in effect a partial closure of the end of said tube, a steel ball adapted to engage said seat to close the discharge end of the tube, and means for moving said ball into and out of contact with said seat to close or open the discharge mouth of said tube, comprising a valve stem mounted for reciprocation and carrying said ball, a spring engaging said stem and constantly urging it to closed position, an eccentric operatively associated with said stem and positioned for engaging same by frictional contact for cocking the valve in open position, a handle for operating said eccentric and arranged to be moved to closed position thereby through the stem moving action of the spring.

5. In a liquid dispensing device, a dispensing

tube, means for connecting the same in communication with a conduit from a source of liquid supply, means for mounting said tube in fixed position, a valve seat member united with the discharge end of said tube and extending beyond the same, said member having a valve seat therein through which the liquid is discharged from the discharge end of said tube, said valve seat located in the discharge mouth of said tube and forming in effect a partial closure of the end of said tube, a metallic ball adapted to engage said

seat to close the discharge end of the tube, said ball located inwardly of said tube from said seat, means extending through said seat for operating said ball including a cam adapted to be releasably cocked in open position by frictional engagement with said plug-operating means, and a liquid discharge conduit extending from said seat and surrounding said means, said conduit having smooth, curved downward contracting uninterrupted walls. 5
